(57) **CLAIM**

The ornamental design for an electric motor mount, as shown and described.

DESCRIPTION

FIG. 1 is a top view of a first portion of an electric motor mount of FIG. 13 showing my new design;

FIG. 2 is a bottom view of the first portion of the electric motor mount of FIG. 13;

FIG. 3 is a front view of the first portion of the electric motor mount of FIG. 13;

FIG. 4 is a rear view of the first portion of the electric motor mount of FIG. 13;

FIG. 5 is a right side view of the first portion of the electric motor mount of FIG. 13;

FIG. 6 is a left side view of the first portion of the electric motor mount of FIG. 13;

FIG. 7 is a top view of a second portion of the electric motor mount of FIG. 13;

FIG. 8 is a bottom view of the second portion of the electric motor mount of FIG. 13;

FIG. 9 is a front view of the second portion of the electric motor mount of FIG. 13;

FIG. 10 is a rear view of the second portion of the electric motor mount of FIG. 13;

FIG. 11 is a right side view of the second portion of the electric motor mount of FIG. 13;

FIG. 12 is a left side view of the second portion of the electric motor mount of FIG. 13;

FIG. 13 is a fully-assembled perspective view of the electric motor mount showing my new design; and,

FIG. 14 is an exploded perspective view of the electric motor mount of FIG. 13.

The broken lines shown in FIGS. 1, 2, 9, and 10 represent the portions of the electric motor mount that form no part of the claimed design. The broken lines shown in FIGS. 13 and 14 represent environmental structure and form no part of the claimed design.

1 Claim, 10 Drawing Sheets
